Patented Oct. 20, 1908.

UNITED STATES PATENT OFFICE.

WILLIAM CHARLES POOLE, OF MARYSVILLE, CALIFORNIA.

CUTTING-TOOL.

No. 901,556.

Specification of Letters Patent.

Patented Oct. 20, 1908.

Application filed February 28, 1908. Serial No. 418,361.

To all whom it may concern:

Be it known that I, WILLIAM C. POOLE, a citizen of the United States, residing at Marysville, in the county of Yuba and State 5 of California, have invented certain new and useful Improvements in Cutting-Tools; and I do declare the following to be a full, clear, and exact description of the invention, such as will enable others skilled in the art to 10 which it appertains to make and use the same.

My invention relates to cutting pliers, and particularly to that type of tool used for trimming horses' hoofs.

15 The object of the invention is to provide a device of this character which will be cheap to manufacture, rapid in operation and which may be conveniently adjusted to determine the cut.

20 A further object of the invention is to provide means for limiting the stroke of the jaws so that the cutting edges of the tool will not come together and be fractured.

In the drawings, Figure 1 is a side elevation, Fig. 2 is a longitudinal section, and Fig. 3 is a detail perspective view of the left jaw. Fig. 4 is a section on the line 4—4 of Fig. 1.

Referring more especially to the drawings, 1 and 2 represent the handles of the device, 25 which are pivoted together adjacent their upper ends by a bolt 3. Each handle has both a pivot and shoulder portion 4 and a recessed portion 5 adapted to receive the shoulder portion of the opposite handle. 30 The shouldered portion of one handle abuts against the shoulder 6 formed in the opposite handle. The jaw 7 is rigidly connected with the handle 2 and the jaw 8 is rigidly connected with the handle 1. Both of the jaws 7 and 8 extend transversely from their respective handles, and the former is curved up into the form of a hook with a portion 9 upon which is formed the cutting edge 10. The latter jaw 8 has an extension 11 substantially 45 parallel with its handle, which extension is provided with a transverse slot 12, through which passes a cutting blade 13, having a cutting edge 14 working in opposition to the cutting edge 10 of the parallel portion 9.

50 This cutting blade extends through the aperture 12, and at its rear end is provided with a depending right angular ear 15 apertured at

16 to receive the adjusting screw 17, which is threaded into the extension 11 and provided with a lock nut 18.

55

The shoulders 4 and 6 are so formed with relation to the pivot bolt 3 that when the jaws are closed in the act of cutting they are stopped temporarily with their cutting edges out of engagement with each other. This 60 temporary stopping of the cutting jaws is caused by the friction of the jaw 4 engaging the lower edge of the jaw 6, which is slightly beveled and over which the jaw 4 is adapted to wipe. It will be seen that if the shoulders 65 4 and 6 of the jaws were formed on a radial line from the pivot bolt that the abutting of the two would be solid, and further movement would be prevented, but as the shoulder 4 is substantially parallel with the longitudinal 70 plane of the tool, and the shoulder 6 is diagonal to said plane the shoulder 4 only engages its lower edge at first. Upon sufficient pressure being exerted upon the operating handles, however, the friction is 75 overcome and the shoulders 4 and 6 will slide over each other to a slight extent and allow the cutting edges to come together. As soon as the handles are released the jaws slide back and separate the cutting edges. This 80 action is possibly due to the fact that the pivot bolt has some inherent resiliency by which the parts are returned to normal. By operating the set screw 18 and the adjusting screw 17 I am enabled to adjust the cutting 85 blade 14 to any required degree so that the cut may be determined to a nicety.

Having thus described my invention what I claim and desire to secure by Letters-Patent is:—

90

1. In a device of the class described, a pair of crossed levers, a pivot bolt connecting said levers, cutting jaws carried by said levers, a shoulder on each lever arranged at a slight angle to the longitudinal plane of the levers, 95 and a shoulder on each jaw formed parallel with the longitudinal plane of said levers and adapted to variably limit the movement of the jaws by wiping over the first mentioned shoulders.

100

2. A cutting tool comprising a pair of crossed levers, a pivot bolt connecting said levers, a cutting jaw integral with one of said levers, the other lever being provided with a

threaded socket and a slot, a cutting bit carried in said slot and having a depending apertured end, and a set screw passing through the depending end and engaging the threaded socket to adjust said cutting bit with respect to said jaw.

In testimony whereof I have hereunto set

my hand in presence of two subscribing witnesses.

WILLIAM CHARLES POOLE.
